UNITED STATES PATENT OFFICE

2,277,316

DOOR HOLDER

Forrest C. Garrison, Highland Park, Ill., assignor
to The Oscar C. Rixson Company, Chicago, Ill.,
a corporation of Illinois

Application January 2, 1941, Serial No. 372,860

5 Claims. (Cl. 292—274)

Door holders, of the class to which this invention relates, hold doors open, when manually stopped, at different positions without interfering with free swing of the door under normal use.

Such a door control, as described by Voight et al., Patent No. 958,477, issued May 12, 1910, is combined with a door closing device. The closing device is of the type having a door operating arm connected at one end to a spring actuated door closing spindle. When the door is opened the door arm rotates the spindle against closing pressure from the spring. To hold the door open, when stopped, at predetermined points upon the opening movement, a pawl, resiliently mounted on the door arm, coacts with lugs circularly grouped on a fixed element surrounding the spindle. The lugs are spaced apart, each lug being shaped to receive the pawl. Otherwise by idly dragging over the lugs, the pawl is ineffective both during opening and closing movements of the door.

At any position of the door at which the pawl is in holding position, freeing the door to permit closing involves an initial further opening of the door sufficient to draw the pawl from engagement with a lug, or the pawl may be forced from the lug by supplementing the action of the closing device sufficiently to overcome yielding resistance from the spring mounting of the pawl.

To prevent the pawl from falling ineffectively between the lugs, the door movement must be halted at invariable positions relative to the lugs. Gauging the precise position at which the door movement should be stopped to cause engagement of the pawl with a lug is an uncertain process, even to one familiar with the lug positions. The difficulty is increased when these lug positions are unknown to the operator.

This objection is removed by the present disclosure, of which the objects are to provide a door controller wherein holding the door open at determined positions does not require special care from the operator, to provide a wide range of closely spaced holding positions, to dispense with individual adjustment of the controller to each door and to provide for normal use of the door without interference from the controller.

The drawings show the improvements specifically embodied.

Figure 1 is a fragmentary perspective of a door controlling installation.

Fig. 2 is a plan view of the controller showing the door and door frame fragmentarily.

Fig. 3 is a central longitudinal section of the

door controller with a holding pawl in engagement.

Fig. 4 is a similar view showing the pawl being forced from engagement.

Fig. 5 shows the pawl out of engagement.

Fig. 6 is a section taken on line 6—6 of Fig. 2.

Fig. 7 is a plan diagram of the door to indicate both free and controller engaging arcs of movement of the door.

Fig. 8 has been added to show a different arrangement of the door controller.

Fig. 9 is a partially sectioned elevation of Fig. 8.

The improved door controller, in common with that of the patented construction above described, uses a pawl and cooperative pawl engaging elements and uses a similar means for placing the pawl in or out of engaging position, but to achieve the above listed objects replaces individual pawl engaging lugs with a pair of spaced plates in each of which are a row of closely spaced pawl sockets. That is, the improved pawl engaging elements instead of comprising short lugs each having a single pawl engaging indentation, with a consequent requirement of nicety in causing engagement of the pawl are in the form of elongated plates each having several pawl engaging indentations. Each of these pawl engaging plates is long enough to permit the door to travel in a wide arc without drawing the pawl from coaction with the plate. Because of the close spacing of the sockets the door may be stopped offhand at any place along either of these arcs and will be held in close approximation to the position desired.

Figure 1 illustrates the device applied to a door 1 which may be equipped with any door closing device. The door is hinged as shown at 2. A groove or track 3 is recessed in the top edge of the door. A pawl carrier 4 slides in the groove and is pivoted at 5 to a door arm 6. A pivot 7 around which the door arm swings is located on the door frame 8. A pawl 9 pivots at 9.1 from a spring mounting 10 on the carrier 4. Pawl engaging racks are formed by a pair of spaced plates 12 and 13 fastened at the bottom of the groove having therein a row of pawl sockets 11. The pawl is pendant when not dragging on the plates.

Opening the door slides the pawl carrier toward the hinge side of the door. The pawl, normally vertical, is knocked to the right as viewed in Fig. 3 by striking plate 12. The pawl rides over sockets 11 and at any place at which opening movement is stopped the pawl will be placed in engagement with the nearest socket under

pressure from the closing device. To disengage the pawl the door is swung open until the pawl has traveled beyond the socket plate and is again free to depend vertically. When rocked to the left, Fig. 5, by plate 12, the pawl may ride thereon ineffectively in either direction. Forced disengagement of the pawl by adding to the pressure from the closing device is provided for by the spring mounting of the pawl (Figs. 3, 4 and 5).

The sockets in plate 12 are for use when the door is to be slightly ajar and the sockets in plate 13 accommodate wider openings. When moving along arcs 12.1 or 13.1 (Fig. 7) the door is positioned for coaction with plates 12 or 13 respectively.

Under ordinary use, the door has no interference by the controller. A usual opening movement, brings the door within the zone of arc 3.1 (Fig. 7) at which position the pawl is between the plates. As the door is closed the pawl is rocked into ineffective position by striking plate 12.

The same principle may be differently applied as illustrated in Figs. 8 and 9 by arcuately arranging two groups of sockets 14 on a table 15 cut at 16 to provide the equivalent of a pair of spaced plates 17 and 18. Table 15 is set at the top of a door closing unit 19 attached to the door 20, and is concentric with a spindle 21. A jointed door operating arm 22 connects the spindle to the door frame 23 and a pawl 24 is pivoted at 24.1 to a spring mounting 25 on the door arm.

Operation of this arrangement is the same as that of the controller of Fig. 2. The pawl is drawn along the sockets for coaction therewith according to door movement. Normal use of the door is unobstructed by the controller, such use moving the pawl ineffectively to and from space 16.

I claim:

1. A door controller including a connection between a door and a door frame, the connection having pivoted attachment points to the door and door frame, a pivoted pendant pawl carried by the connection, a pair of plates spaced apart and positioned on the door below the pawl in the

path thereof for coaction with the pawl, and a plurality of pawl sockets in each plate.

2. A door controller including a pivot for attachment to a door, a pair of plates on the door, the plates being spaced apart and having therein pawl sockets arcuately arranged around the pivot, a door arm connected at one end to said pivot and having a pivot connection at the other end for attachment to the door frame, a normally pendant pawl pivoted to the arm and positioned to be brought into coaction with the pawl sockets by movement of the arm.

3. A door controller including a pivot for attachment to a door, a pair of plates on the door, the plates being spaced apart and having therein pawl sockets arcuately arranged around the pivot, a door arm connected at one end to said pivot and having a pivot connection at the other end for attachment to the door frame, a spring mounting on the arm, a normally pendant pawl pivoted to the spring mounting and positioned to be brought into coaction with the pawl sockets by movement of the arm.

4. A door controller including a track for attachment to a door, a pawl carrier slidable on the track and a normally pendant pawl pivoted on the carrier, an arm having a pivot connection at one end to a carrier and a pivot connection at the other end for attachment to the door frame, a pair of plates spaced apart and positioned below the pawl in the path thereof for coaction with the pawl, and a plurality of pawl sockets in each plate.

5. A door controller including a track for attachment to a door, a pawl carrier slidable on the track, a spring mounting on the carrier and a normally pendant pawl pivoted on the mounting, a door arm having a pivot connection at one end to the carrier and a pivot connection at the other end for attachment to the door frame, a pair of plates spaced apart and positioned below the pawl in the path thereof for coaction with the pawl, and a plurality of pawl sockets in each plate.

FORREST C. GARRISON.
